UNITED STATES PATENT OFFICE.

JAMES M. MERRITT, OF LOS ANGELES, CALIFORNIA.

DESIGN FOR A STOVE-TOP.

45,945.

Specification for Design.

Patented June 16, 1914.

Application filed April 4, 1914. Serial No. 829,712. Term of patent 7 years.

To all whom it may concern:

Be it known that I, JAMES M. MERRITT, a citizen of the United States, residing at Los Angeles, in the county of Los Angeles, State of California, have invented a new, original, and ornamental Design for Stove-Tops, of which the following is a specification, reference being had to the accompanying drawing, forming part thereof.

The figure is a perspective view of a stove top, showing my new design, the body of

the top being in black finish and the encircling rim and the urn being in white finish, preferably nickelated.

I claim:

The ornamental design for a stove top, as shown.

J. M. MERRITT.
